UNITED STATES PATENT OFFICE

166,593

SUCTION CLEANER OR SIMILAR ARTICLE

Peter W. Cherry, Milford, Conn., assignor to General Electric Company, a corporation of New York

Application June 6, 1950, Serial No. 10,382

Term of patent 14 years

(Cl. D9—2)

To all whom it may concern:

Be it known that I, Peter W. Cherry, a citizen of the United States, residing at Milford, in the county of New Haven, Connecticut, have invented a new, original, and ornamental Design for a Suction Cleaner or Similar Article, of which the following is a specification, reference being made to the accompanying drawing, forming part thereof.

In the drawing, Fig. 1 is a side view of a suction cleaner showing my new design applied thereto; Fig. 2 is a plan view of the same; and Fig. 3 is an enlarged right hand end view of a portion of Fig. 2.

The essential features of the design reside in the handle and escutcheon portions shown in full lines.

I claim:

The ornamental design for a suction cleaner or similar article, substantially as shown and described.

PETER W. CHERRY.
